UNITED STATES PATENT OFFICE

ROY C. BAKER, OF WOLLASTON, MASSACHUSETTS, ASSIGNOR OF ONE-FIFTH TO LOUIS A. JONES, OF BELMONT, MASSACHUSETTS

METHOD OF AND APPARATUS FOR PRODUCING MATRICES

Application filed July 17, 1929. Serial No. 378,879.

This application relates to a novel apparatus for producing matrices used for casting stereotype plates. The method in common use involves the idea of pressing or beating the soft, moist paper into the type. In the production of matrices for book plates, the paper must be beaten in to a good depth to produce a clear sharp impression in the subsequent printing from the plate. This is a slow, laborious, and therefore expensive, operation, and at best does not produce altogether satisfactory results, particularly on closed letters, such as a, b, d, e, g, o, p and others, because a certain amount of air is bound to be trapped in the closed depressions, thereby preventing the paper from reaching the full depth of the letter. These difficulties and disadvantages are avoided by the use of my improved apparatus.

The invention will be best understood by reference to the following description, when taken in connection with the accompanying drawing of one specific apparatus embodying the invention, while its scope will be more particularly pointed out in the appended claims.

In the drawing:

Fig. 1 is an elevation of the apparatus, minus the suction and compression pumps; Fig. 2 is a plan of the apparatus, minus the clamping means; and

Fig. 3 is a sectional view at an enlarged scale on line 3—3 of Fig. 2.

Referring to the drawing and to the embodiment of the apparatus illustrated therein, there is shown a page of type 5 (see Fig. 3), held in a chase 6 in the usual manner. Superimposed upon the type faces is a sheet of soft, moist paper 7, which some stereotypers call the "mat". These parts are placed in a closed chamber 8, comprising a casing 9 closed at the top by a flexible wall, such as a rubber blanket 10, whose margin overlies the margin of the casing. Air is exhausted from this chamber by the use of an appropriate suction pump 11 (see Fig. 2), connected to the chamber by a pipe 12.

The margin of the blanket is clamped to provide a seal, by the use of a second casing 13, which may be secured to the first casing

by any suitable means, such as a press 14, having a base 15, a clamping plate 16, and a clamping screw 17, provided with a hand-wheel 18. It should be understood, of course, that this clamping means is merely typical, and that other means may be provided for securing the two parts of the casing together. The means shown, however, is convenient, because it interferes in no way with the margin of the blanket.

When air is exhausted from the chamber 8, the paper can be forced into the type to the full depth, because no air pockets are formed in the type faces. While air at atmospheric pressure might be admitted into the casing 13, and thus serve to cause the blanket to press the paper into the type, in the present example, the upper casing 13 has a chamber 14, to which any fluid such as air, steam or water under pressure, may be admitted. In the present example, the casing 13 is connected by a flexible conduit 15 to an air compressor 16, by means of which the chamber may be supplied with air under considerable pressure. Thus, by exhausting air from the lower chamber and supplying compressed air to the upper chamber, the blanket is caused to press the paper "mat" into the type.

If desired, there may be provided mechanical means for pressing the blanket against the type face, and, as shown in the drawing, I have provided for this purpose a roller 17 of suitable resilient material such as rubber, to which pressure may be applied, as by mounting the roller on a shaft 18, having at each end a roller 19 running in a horizontal groove 20 presented by a track 21, which is free to move vertically and is urged in a downward direction by springs 22, to which pressure may be applied by screws 23. As shown, the springs surround rods 24, which are attached to the tracks and extend vertically through the screws. Sealing caps 25, which enclose the upper ends of the screws and the rods to prevent the entrance of air, are threaded onto bosses 26 presented by the casing 13, gaskets or washers 27 of suitable soft material such as lead being provided between the caps and the casing. Downward

movement of the track under the influence of the springs when the upper casing is lifted may be limited by suitable means, such as studs 28 secured to the casing, and extending through slots 29 presented by the track.

5 The roller may be moved to and fro by the use of a yoke 30 attached to the shaft and pivotally connected to a rod 31 (see Fig. 2), which extends through a stuffing box 32 to the 10 exterior of the casing. Reciprocation of this rod will cause the roller to travel back and forth across the blanket.

15 By the use of the described apparatus, the paper "mat" is forced into the type faces to the full depth, thereby producing a matrix from which there can be cast a stereotype which will produce a clear, sharp impression, and yet the method is rapid and inexpensive.

20 Having thus described the preferred apparatus, but without limiting myself thereto, what I claim and desire by Letters Patent to secure is:

1. Matrix producing apparatus comprising, in combination, means forming a sealed 25 chamber for the type and the matrix paper, said chamber having a flexible wall, and means for exhausting air from said chamber and causing said wall to urge said paper against the type face.

30 2. Matrix producing apparatus comprising, in combination, means forming a sealed chamber for the type and the matrix paper, said chamber having a flexible wall, means 35 for exhausting air from said chamber, and means for applying fluid pressure to the outer surface of said wall.

3. Matrix producing apparatus comprising, in combination, means forming a sealed 40 chamber for the type and the matrix paper, said chamber having a flexible wall, means for exhausting air from said chamber, and means for applying mechanical pressure to the outer surface of said wall.

4. Matrix producing apparatus comprising, in combination, means forming a sealed 45 chamber for the type and the matrix paper, said chamber having a flexible wall, means for exhausting air from said chamber, and means for applying fluid and mechanical pressure to the outer surface of said wall.

50 5. Matrix producing apparatus comprising, in combination, two casing parts and an interposed flexible wall forming a suction chamber for the type-form and the matrix paper at one side of said wall and a pressure chamber at the other side of said wall, means for exhausting air from said suction chamber, and means for supplying fluid under pressure to said pressure chamber.

55 6. Matrix producing apparatus comprising, in combination, two casing parts and an interposed flexible wall forming a suction chamber for the type-form and the matrix paper at one side of said wall and a pressure chamber at the other side of said wall, means

for exhausting air from said suction chamber, means for supplying fluid under pressure to said pressure chamber, and mechanical pressure means within said pressure chamber for causing said wall to press said matrix paper against said type-form.

7. Matrix producing apparatus comprising, in combination, two casing parts and an interposed flexible wall forming a suction chamber for the type-form and the matrix paper at one side of said wall and a pressure chamber at the other side of said wall, means for exhausting air from said suction chamber, means for supplying fluid under pressure to said pressure chamber, and mechanical pressure means including a spring-pressed roller within said pressure chamber for causing said wall to press said matrix paper against said type-form.

8. Matrix producing apparatus comprising, in combination, two casing parts and an interposed flexible wall forming a suction chamber for the type-form and the matrix paper at one side of said wall and a pressure chamber at the other side of said wall, means for exhausting air from said suction chamber, means for supplying fluid under pressure to said pressure chamber, and mechanical pressure means including a spring-pressed roller and roller operating means within said pressure chamber for causing said wall to press said matrix paper against said type-form.

9. Matrix producing apparatus comprising, in combination, two casing parts and an interposed flexible wall forming a suction chamber for the type-form and the matrix paper at one side of said wall and a pressure chamber at the other side of said wall, means for exhausting air from said suction chamber, means for supplying fluid under pressure to said pressure chamber, and mechanical pressure means including a resilient roller within said pressure chamber for causing said wall to press said matrix paper against said type-form.

10. Matrix producing apparatus comprising, in combination, means forming a closed chamber having a flexible, imperforate wall, type within said chamber, said type facing toward said wall, there being a space between said wall and the type face for the matrix paper, and means for exhausting air from said chamber thereby to cause said wall to urge the paper against the type face.

11. Matrix producing apparatus comprising, in combination, means forming a closed chamber having a flexible, imperforate wall, type within said chamber, said type facing toward said wall, there being a space between said wall and the type face for the matrix paper, and means for exhausting air from said chamber and applying fluid pressure to the outer surface of said wall, thereby to cause said wall to urge the paper against the type face.

12. Matrix producing apparatus comprising, in combination, means forming a closed chamber for the type and the matrix paper, said means comprising a wall movable toward the type face, and means for exhausting air from said chamber.

13. Matrix producing apparatus comprising, in combination, means forming a closed chamber for the type and the matrix paper, said means comprising a wall having a flexible face movable toward the type face, and means for exhausting air from said chamber.

14. Matrix producing apparatus comprising, in combination, means forming a closed chamber for the type and the matrix paper, said means comprising a flexible wall movable toward the type face, and means for exhausting air from said chamber.

15. Matrix producing apparatus comprising, in combination, means forming a closed chamber for the type and the matrix paper, means for exhausting air from said chamber, and means for causing the matrix paper to be urged against the type face while there is a lowered air pressure in said chamber.

16. Matrix producing apparatus comprising, in combination, means forming a closed chamber for the type and the matrix paper, means for exhausting air from said chamber, and means including a flexible body for pressing the matrix paper against the type face.

17. Matrix producing apparatus comprising, in combination, a casing provided with a chamber having an opening through which the type and the matrix paper may be introduced into said chamber with the type face directed toward said opening and with the matrix paper superimposed upon the type face, means presenting a closure for said opening and a pressure member for pressing the matrix paper upon the type face, and means for exhausting air from said chamber.

45 In testimony whereof I have signed my name to this specification.

ROY C. BAKER.
